UNITED STATES PATENT OFFICE

ALFONSO GANDOLFO AND BATTISTA LEMANDRI, OF BROOKLYN, NEW YORK

ORNAMENTAL VALANCE

Application filed September 11, 1930. Serial No. 481,220.

This invention relates to new and useful improvements in an ornamental valance.

In the hanging of curtains it is general practice to provide curtain rods which are attached across the tops of windows and upon which curtains are supported. It is conventional to make these curtain rods adjustable to fit windows of different widths.

It is an object of this invention to further 10 ornament the curtains by the provision of a valance arranged for being mounted upon the top of the curtains and particularly upon the curtain rods so as to finish the top marginal edges of the curtains. It is also proposed to make the valance adjustable in a 15 manner so as to fit the adjustability of the curtain rods.

It is also an object of this invention to provide a device of the class mentioned 20 which is of simple durable construction, dependable in use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front elevational view of an ornamental valance constructed according to 35 this invention.

Fig. 2 is an enlarged vertical sectional view taken on the line 2—2 of Fig. 1.

Fig. 3 is a top plan view of the valance and the curtain rod.

40 Fig. 4 is a front elevational view similar to Fig. 1, but illustrating a valance of modified form.

Fig. 5 is a sectional view taken on the line 5—5 of Fig. 4.

45 Fig. 6 is a fragmentary sectional view taken on the line 6—6 of Fig. 5.

Fig. 7 is a front elevational view of the wire frame used in the valance shown in Fig. 4.

50 Fig. 8 is a plan view of Fig. 7.

Fig. 9 is a view similar to a portion of Fig. 2, but illustrating a modification.

The ornamental valance comprises ornamental end sections 10 and 11 telescopically arranged with a central section 12 for adjustments to different widths of windows, and means for supporting the combined sections upon a curtain rod such as illustrated and indicated by reference numeral 13.

In Figs. 1 to 3 the central section 12 is 60 shown of shield form, that is, it is quite large and formed of an ornamental shape with points at the top and bottom. Of course, it may be of any other design and construction. It is also formed at its rear side with opposed 65 longitudinal edges turned backwards toward each other and indicated by reference numerals 14. These turned edges receive the ends of the end sections 10 and 11 and accomplish the telescopic arrangement. The end sections 10 and 11 are formed with a fringed bottom 15. It is intended that all of the sections be suitably ornamented or covered with suitable lace or other ornamental material so as to match with the curtains in conjunction with which they are used.

The outer ends of the sections 10 and 11 are bent rearwards as indicated by reference numerals 16 so as to correspond with the rearward bent edges 17 of the curtain support rods 13. The means for supporting the combined sections upon the curtain rod 13 comprises a plurality of hooks 18 projecting from the various sections, and directed downwards so as to be engageable over the top 85 edge of the curtain rod 13. These hooks are arranged along the longitudinal lengths of the various sections and also along the rearward turned end 16 so that when engaged upon the curtain rod firm supporting is accomplished. In Fig. 3 the curtain rod 13 is shown projecting from a wall 19.

In Figs. 4 to 8 inclusive a modified form of valance has been illustrated. This valance is also formed of three sections, namely a 95 central section 20 and end sections 21 and 22, respectively. The central section 20 is of shield form and the end sections 21 and 22 have straight edges. The various sections are telescopically arranged. This is accom-

plished by tubes 23 attached upon the central section and telescopically receiving the ends of the end sections 21 and 22. The various sections are formed by wire frames and cloth material engaged upon these frames. This is very clearly illustrated in Figs. 5 to 8 inclusive.

In Figs. 7 and 8 particularly, just the end sections are shown. The end sections 21 and 22 are shown engaging the tubular elements 23. Hooks 24 project from vertical braces 25 included in the frames forming the end sections 21 and 22 for engaging upon the curtain rod in a manner similar to the one previously described. In Figs. 4, 5 and 6, cloth material 26 is shown engaged over the sections so as to cover them and expose an ornamental effect. This cloth is suitably ornamented by flowers as indicated by reference numeral 27, or any other ornamental arrangement. The manner of attaching the cloth upon the frames used in the sections consists in turning the marginal edges 28 of the cloth over the edges of the frame and then lacing strings 29 through these marginal edges. This arrangement allows the removal of the cloth for washing when the curtains are sent to be washed. After suitable washing, they may again be engaged upon the wire frames.

In Fig. 5 a wall 31 has been illustrated to which a curtain rod 32 is attached. Hooks 24 are shown engaging over the top of the curtain 32 for holding the ornamental valance in place. Of course, curtains should also be engaged over the curtain rods 32 as is conventional.

In the modified form of the device illustrated in Fig. 9, a means has been shown for supporting the combined sections adjustably upon a curtain rod. This would allow a change of the distance between the valance and the ceiling of a room so as to change the ornamental effect and position the valance at the artistic beautiful point. This means for accomplishing the adjustable supporting comprises a plurality of hooks 33 frictionally engaged upon pairs of vertical rods 34 attached upon the rear of the ornamental valance. These rods are slightly spaced farther apart from each other than the apertures through the hooks so that they are slightly bowed and thus provide sufficient friction for maintaining adjusted positions of the hooks. The hooks 33 are intended for engagement upon the curtain rods as previously described. When they are forced to different positions along the rods, the valance will be raised or lowered since the curtain rod is permanently attached upon the window of the room.

It is to be understood that our ornamental valance may be of mica, parchment, fiber, cloth or any other suitable material.

While we have shown and described the

preferred embodiment of our invention, it is to be understood that we do not limit ourselves to the precise construction herein disclosed and the right is reserved to all changes and modifications coming within the scope of the invention as defined in the appended claims.

Having thus described our invention, what we claim as new, and desire to secure by United States Letters Patent is:—

1. An ornamental valance, comprising ornamental sections telescopically engaging each other for adjustments to different widths of windows, and means for supporting the combined sections on a curtain rod, said latter means being in different horizontal planes, the adjustability of supporting being accomplished by hooks slidably engaged upon vertical rods attached upon the rears of said sections.

2. An ornamental valance, comprising ornamental sections telescopically engaging each other for adjustments to different widths of windows, and means for supporting the combined sections on a curtain rod, said latter means being adjustable for supporting the combined sections in different horizontal planes, said means comprising hooks formed with apertures, vertical rods spaced farther apart from each other than the apertures formed in the hooks so that the rods are slightly bowed so as to provide sufficient friction for maintaining adjusted positions of the hooks.

3. An ornamental valance, comprising ornamental sections telescopically engaging each other for adjustments to different widths of windows, and means for supporting the combined sections on a curtain rod, in different horizontal planes comprising hooks slidably mounted on the rears of said sections.

4. An ornamental valance, comprising ornamental sections telescopically engaging each other for adjustments to different widths of windows, and means for supporting the combined sections on a curtain rod, in different horizontal planes comprising hooks formed with two apertures, two vertical rods attached to the rears of the sections and engaging said apertures in the hooks, and means for maintaining relative positions between the hooks and the rods.

In testimony whereof we have affixed our signatures.

ALFONSO GANDOLFO.
BATTISTA LEMANDRI.
